UNITED STATES PATENT OFFICE.

BERNARD E. WALBERG, OF WORCESTER, MASSACHUSETTS.

CIGAR AND CIGARETTE HOLDER.

Application filed June 17, 1926. Serial No. 116,729.

This invention relates to a combined cigar and cigarette holder.

The principal objects of the invention are to provide a holder which will have two arms operated by the action of gravity instead of by spring pressure to hold either a cigar or cigarette in the same structure; to provide means whereby the pressure will not be dependent on the compression of springs and which will vary only slightly, but will be greater in the case of a cigar than in the case of a cigarette; to provide a construction in which the arms for holding the cigar or cigarette normally are held slightly apart so that in placing a cigarette between them very little force will have to be used; and to provide a cigar and cigarette support in connection with these arms in a convenient position and of small size.

Other objects and advantages of the invention will appear hereinafter.

Reference is to be had to the accompanying drawings in which

Fig. 1 is a side view, partly broken away to show the interior construction, of a preferred embodiment of this invention;

Fig. 2 is a plan of the same; and

Fig. 3 is a sectional view on the line 3—3 of Fig. 2 showing most of the parts in end elevation and illustrating another position of one of the parts in dotted lines.

The device is shown as supported by a bracket which has a flat base 11 of large size and preferably circular in shape. This can be attached to a vertical wall as shown in Fig. 1 or it can be swung down as shown in dotted lines in Fig. 3, to support the device on a horizontal surface. In fact it can be adjusted to be supported on an inclined surface. This bracket has two parallel arms 10 projecting oppositely from it and each having a concave cup shaped end 12 and formed of a single piece of sheet metal.

Between the cup-shaped ends 12 I show supported an ash receiver consisting of two parts 13 and 14 which may be of globular form. The two arms 10 of the bracket are, of course, resilient, being made of sheet metal preferably, and they hold the two concave ends 12 against opposite sides of the globular ash receiver to support it and hold it in any desired position to which it may be turned. The ash receptacle can be pulled out of the bracket without any adjustment or the detachment of any screws or

fastening devices and can be inserted in a quick and simple way.

The two parts 13 and 14 of the ash receiver are hemispherical in the form shown and provided with a joint 15 to hold the two parts together by friction so that ordinarily they will not come apart but so that they can be separated for cleaning. The concave ends 12 also assist in holding them together.

At the top of the receiver there is a circular ash tray 16 of conical or cup-shaped form integral with the part 14 of the ash receiver and having an opening 17 through which the ashes drop. These parts constitute the ash tray and receiver themselves.

The ash tray 16 is provided, either integral with it or attached to it, with a plate 20 which is bent down to form a U-shaped construction 21 and then bent outwardly to form a cigar and cigarette rest 22. This is shown as having a narrow portion 23 and a pair of arms 24 at the end bent upwardly at their ends so as to fit the cigar and hold the cigarette.

In the top of the U-shaped part 21 is a stud or rivet 25 extending across it longitudinally of the cigar rest 22. On this are pivoted two wires or arms 26 oppositely twisted around the pivot 25 so as to swing freely thereon and each having an upward extension 27 and a lower extension on which there is a weight 28. These upward extensions are spread out at the top so that they will receive a cigar or cigarette if let down into them and they bow out from that to hold it afterward. The weights can go down no further than the U-shaped construction 21 so that they act as stops to bring the wires slightly apart at their nearest points. This is provided so that it will be easier to insert the cigarette without danger of injuring it and so that there will be no danger of any part catching or holding when a cigar is placed in it.

By providing a weight instead of a spring device, the whole thing works easier and it will never get out of order on account of a spring losing its resiliency. Furthermore the weights permit the construction above described so as to keep the arms apart and they do not limit the width of the holder so that the construction is suitable for a cigar or cigarette.

I have found in practice that these wires 26 conduct the heat away so fast that if a

cigarette is put in it, it will continue to burn only up to these wires and then go out. The ashes, of course, fall into the ash receiver 16 which can be removed readily and cleaned 5 and replaced.

The full line drawings show the device having the bracket fixed to a vertical wall. In dotted lines I have shown it to be down to the bottom so that the device will rest 10 on a table or desk or other horizontal surface without fastening it. It can be swung out angularly so that it can be attached to an inclined surface, leaving the rest of the device in an upright position without needing 15 any other adjustments.

Although I have illustrated and described only one form of the invention, I am aware of the fact that modifications can be made therein by any person skilled in the art without departing from the scope of the invention as expressed in the claims. Therefore, I do not wish to be limited to all the details 20 of construction, but what I do claim is:—

1. As an article of manufacture, a cigar or cigarette holder comprising a pair of arms pivoted on the same axis each having an upwardly extending portion adapted to grasp a cigar or cigarette between them and provided with weights on them to tend to 25 force them together by the action of gravity.

2. As an article of manufacture, a cigar or cigarette holder comprising a pair of crossing pivoted wires, each having a weight at its lower end for normally holding the wires near together, the wires having arms 30 projecting upwardly bowed outwardly at the point at which the article is to be held and having outwardly extending and slanting ends.

3. As an article of manufacture, a cigar 40 or cigarette holder comprising a stud, a pair of crossing pivoted wires, each one twisted about the stud and each having a solid weight at its lower end for normally holding the wires as near together as possible, the wires having arms projecting upwardly bowed outwardly at the point at which the article is to be held and having outwardly extending and slanting ends spaced apart for facilitating the application of a cigar 45 or cigarette thereto.

4. As an article of manufacture, a cigar or cigarette holder comprising a stud, a pair of wires twisted oppositely about the stud 50 and each having a weight at its lower end for normally holding the arms as near together as possible, the wires having arms projecting upwardly to hold the article between them and having outwardly extending 55 and slanting ends for facilitating the application of a cigar or cigarette thereto, and means for limiting the descent of the weights to hold the arms out of contact at their nearest point above the pivot.

5. As an article of manufacture, a cigar or cigarette holder comprising a pair of arms pivoted on the same axis each having an upwardly extending portion adapted to grasp a cigar or cigarette between them and provided with weights on them adapted to 60 hold an article placed between them, and a substantially horizontal rest projecting out from a point adjacent to the pivot for the purpose described.

In testimony whereof, I have hereunto 70 affixed my signature.

BERNARD E. WALBERG.
